UNITED STATES PATENT OFFICE.

FRANK C. MOCK, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,395,233.

Specification of Letters Patent. Patented Oct. 25, 1921.

Application filed August 23, 1915. Serial No. 46,774.

To all whom it may concern:

Be it known that I, FRANK C. Mock, a citizen of the United States, residing at Chicago, in the county of Cook and State of Illinois, have invented a certain new and useful Improvement in Carbureters, of which the following is a full, clear, concise and exact description, reference being had to the accompanying drawings, forming a part of this specification.

My invention relates to carbureters for internal-combustion engines and is concerned particularly with the provision of means for feeding additional liquid fuel to the mixture upon acceleration.

The desirability of feeding extra gasoline, assuming that to be the liquid fuel employed, to the mixture upon acceleration, that is, at the beginning of a period of increased suction, is well known in the art. This desirability follows from the natural inertia of the fuel from the main source, and the lag with which the feed of fuel, being heavier than air, follows the position of the throttle, and is also due to the increased effort of the engine at that particular time. It is obvious that this extra feed of gasoline should be merely temporary, since, once the increased suction has become effective on the main source, the conditions are steady and further additional gasoline would be excessive. It is also understood that when the engine is cool more gasoline is required than when it is warmer, and it will be understood that this temporary feed of gasoline corresponds with these conditions.

In accordance with my invention, I provide a U-shaped well, one arm of which is subject to suction, and the other arm of which is open to atmosphere sufficiently to secure the desired results. The last-mentioned arm has a fuel-jet leading therefrom, this jet lying above the normal level of the gasoline as determined by a constant-level device.

It will become apparent that when suction is applied to the first-mentioned arm the gasoline therein will rise above the normal level. Then, upon a reduction of the suction in that arm, there will be a tendency for the gasoline in the two arms to assume the same level. This brings the gasoline in the other arm up to or beyond the level of the fuel-nozzle and a temporary feed results.

My invention will be clearly understood

by reference to the accompanying drawings, in which:

Figure 1 is, in the main, a vertical axial section view;

Fig. 2 is a partial plan view;

Fig. 3 is an axial sectional view taken on the plane of the line 3-3 of Fig. 2 and looking in the direction indicated by the arrows;

Fig. 4 is a sectional view taken on the plane of the line 4-4 of Fig. 2 and looking in the direction indicated by the arrows;

Fig. 5 is a sectional view taken on the plane of the line 5-5 of Fig. 2 and looking in the direction indicated by the arrows;

Figs. 6, 7 and 8 are more or less diagrammatic views illustrating the operation which I shall describe.

I have illustrated my invention applied to the type of carbureter commonly known as an auxiliary air-valve device. In this structure a casing 9 provides a carbureting chamber 10, into which a Venturi tube 11 leads, the primary intake for air being connected with this Venturi tube by means of the passageway 12. A manually-operated choker-valve 13 is disposed in this primary air-intake.

Auxiliary air is admitted into the carbureting chamber 10 by way of an opening 14, which is controlled by an automatically-operating valve 15. Since my invention is not concerned with the details of this valve, the adjustments therefor, etc., I shall not burden this specification with a description of these details. It is sufficient to say that the valve 15 responds to suction to admit additional air, and that with this additional air additional fuel is admitted, it being understood that this valve does not open until the higher suction are attained. Briefly, this is accomplished in the following manner: A piston 16 is connected with the valve 15 by means of a stem 17, this piston operating in a chamber 18, to which gasoline is admitted in a manner to be described presently. The operation of the piston in the gasoline retards the opening movement of the valve.

An auxiliary fuel-nozzle 19 is carried by the valve 15, and by means of a passageway through the stem 17 this nozzle is connected with the gasoline in the chamber 18. A valve 20 controls the passageway through the stem 17, and it will now be clear that

when the valve 15 comes down the valve-seat 21 for the valve 20 leaves the valve 20 and permits the flow of gasoline thereby.

A bridge 22 spans the passageway 12 and supports the main fuel-nozzle 23 within the Venturi tube, as shown. Gasoline is supplied to this nozzle from the float-chamber 24, by way of the passageway 25, the gasoline being maintained at approximately the 10 level of the dot-and-dash line X—X by the float-chamber mechanism. The gasoline passageway 25 is extended at 26 to connect with the chamber 18, as hereinbefore referred to. Gasoline is supplied to the float-chamber 24 by means of the pipe 27.

The mixture-outlet is illustrated at 28, and a butterfly throttle-valve 29 is provided in this outlet, there being a slight opening around the valve when the valve is in its 20 closed position.

It will be seen from Fig. 4 that I provide two vertical passageways, both extending upwardly from the plane of the gasoline passageway 25, one extending upwardly to a 25 point above the throttle. I have indicated these passageways at 30 and 31, and it will be seen that at the bottom they are connected together by means of the passageway 32, and with the gasoline passageway 25 by 30 means of the passageway 33, this last-named passageway being considerably restricted, as shown.

As shown in Figs. 1, 4 and 5, the passageway 31, at the top thereof, is provided with 35 a passageway 34, leading to a point above the throttle, where it will be subject to suction. An atmosphere-inlet 35 is also provided for the passageway 31.

The passageway 30 is provided with a 40 laterally-extending gasoline-nozzle 36, which extends radially into the Venturi tube 11, opening into the interior thereof, as illustrated in Figs. 1 and 3. The nozzle 36 is disposed above the normal level of the gasoline 45 as determined by the constant-level mechanism in the float-chamber 24. The top of the passageway 30 is connected with the atmosphere by means of the passageway 37.

For convenience, I shall refer to the combined passageways 30, 31 and 32 as a U-shaped tube, and it will now be seen that gasoline is fed to the bottom of this U-shaped tube and that, with the engine at rest, gasoline stands in both arms of the 55 U-shaped tube to the level of the dot-and-dash line X—X. It will be kept in mind that, so long as the throttle forms any obstruction in the mixture-outlet, there is a difference in pressure on opposite sides thereof, and it will also be understood that, as the throttle is gradually opened, this difference in pressure decreases, whereas, as the throttle is closed, the difference in pressure increases. The operation of the device of my invention 60 will be best understood by reference to Figs.

6, 7 and 8, wherein Fig. 6 shows the idling or low-running position. In this idling or low-running position the throttle is closed except for a small opening around it, and there is a limited feed from the main nozzle 23. 70 Under some circumstances an idling or low-running feed may be led directly above the throttle, or at least placed in close proximity to the throttle, but it will be clear that such a difference in no wise changes the operation of the essential features of my invention, which are concerned with acceleration. In other words, the accelerating well of my invention and the parts necessarily concerned in it operate the same whether the main fuel 75 is fed by a separate jet or not, or whether the main fuel is fed by one or two jets. I desire that the scope of my invention shall be determined by the appended claims and not be limited to any precise details which I 80 describe as an exemplary embodiment of my invention.

It will be seen that, with the throttle in the position shown in Fig. 6, there will be a great suction above the throttle, and this 90 suction is transmitted to the arm 31 of the U-shaped well by way of the passageway 34. In view of the large range of suction above the throttle, and the limited space for the passageway 31, as well as the limited amount 95 of fuel required for acceleration, I provide means whereby the suction above the throttle shall not be fully effective in the arm 31 of the U-shaped well. As before described, I bleed this well to the atmosphere by way 100 of the opening 35, in order that only a certain proportion of the suction, dependent upon the sizes of the passageways, may be effective in the arm 31. Be it understood, however, that suction above the throttle is 105 effective in the arm 31 to raise the gasoline in that arm considerably above the dot-and-dash line, that is, the fuel-level, it being remembered that there is a constant head tending to move fuel into this well. There 110 is, of course, a certain reduction of pressure during this period, at the outlet of the nozzle 36, but under these conditions this reduction of pressure is negligible, first, because it is small, and, second, because the 115 nozzle 36 is disposed above the normal level of the gasoline sufficiently so that any slight rise of the gasoline in the arm 30 could be disregarded. It also will be seen that the arm 30 is open to atmosphere by way of the 120 passage 37, and, although it would not vitiate the operation if there were sub-atmosphere in the arm 30, it is desirable to keep the pressure in that arm as near atmosphere as possible. It will thus be seen that 125 in the idling or low-running position any suction at the nozzle 36 would be satisfied by the opening 37, but if not fully satisfied thereby the rise of fuel due to such reduction in pressure would be so small as to be 130

negligible. Therefore, the nozzle or fuel inlet 36 feeds fuel only upon a sudden opening of the throttle, that is, when it is desired to accelerate. Thus, by the communication 5 of the passageway 30 with atmospheric pressure at all times, the accelerating well will work at all speeds, so that if the motor vehicle is running at a moderate speed and a sudden acceleration is desired, the well will 10 function. Hence, the well is operable throughout the range of motor speed to give the desired acceleration at any time.

Referring now to Fig. 7, it will be seen that the throttle has been opened. The result 15 is a great reduction in the suction at the passageway 34, with a consequent increase in pressure in the arm 31 of the U-shaped tube amounting to substantially atmosphere, in view of the bleed 35. There 20 is then immediately a tendency for the fuel in the U-shaped tube to equalize the level in both arms, with the result that the gasoline quickly drops in the arm 31 and rises in the arm 30. This action is immediate and 25 overwhelming, and any passage of fuel through the restricted passageway 33, is negligible at this instant. The rise of fuel in the arm 30 of the U-shaped tube produces a head of fuel above the accelerating nozzle 36, and this head of fuel therefore issues 30 from this nozzle, in addition to the flow from the nozzle 23, until the head has become exhausted. Since the amount of gasoline over the nozzle 36 is limited, it will be 35 clear that the surcharging of the mixture will be merely temporary. It will be clear that the operation is the same in kind, though not in degree, for any change in the position of the throttle which reduces 40 the suction above the throttle—any accelerating action—whether the condition changes from one of minimum running to a higher speed, or from an intermediate speed to a higher one.

45 When the throttle is closed down again, as illustrated in Fig. 8, the column of gasoline in the passageway 31 will be drawn upwardly, causing the column in the arm 30 to drop. There is, however, a feed into the 50 U-shaped tube from the float-chamber by way of the passageway 33, and the conditions shown in Fig. 6 are rapidly resumed, so that an extra charge may again stand ready for the next acceleration.

55 It will be seen that the amount of suction effective on the passageway 34 determines the height to which the gasoline in the arm 31 of the U-shaped tube rises, which, in turn, determines the amount of the accelerating 60 charge. For a slight change in position of the throttle, toward the open position, the unbalancing of the two arms of the U will be correspondingly slight and the surcharge correspondingly small. It is possible that 65 means other than the throttle could be pro-

vided to control the suction which causes the rise of the gasoline in the arm 31, and some of the appended claims have been drawn with that in mind. I have illustrated, approximately, the comparative 70 sizes of the various passageways, as determined by experiments which I have conducted. Sizes used were as follows: passageways 33 and 34, .040 inch in diameter and passageway 35, .136 inch in diameter. 75 These experiments showed, however, that the comparative sizes could be departed from without departing from the fundamental operation involved, and I therefore assume that any sizes, or comparative sizes, 80 which maintain the mode of operation and results which I have described, come within the spirit and scope of my invention.

I claim:

1. In a carbureter, a carbureting chamber 85 having an air inlet and a mixture outlet, a throttle controlling said outlet, a constant level liquid fuel supply chamber, a fuel inlet for said carbureting chamber, a passageway leading from said fuel supply 90 chamber to said fuel inlet and having a restriction therein, a well connected to said passageway between said restriction and said fuel inlet, said well, above the fuel level therein, being connected by a passageway for 95 air only with the mixture outlet, whereby the partial vacuum applied to said well when the throttle approaches closed position causes liquid fuel to rise therein to a level above that of the fuel in the constant 100 level chamber, the opening of the throttle reducing said vacuum and permitting said fuel to drop and feed to said fuel inlet.

2. In a carbureter, a carbureting chamber having an air inlet and a mixture outlet, 105 a throttle controlling said outlet, a constant level liquid fuel supply chamber, a fuel nozzle extending into said carbureting chamber and fed from said supply chamber, a U-shaped well fed from said supply 110 chamber, and a fuel nozzle leading from one arm of said well above the normal level of liquid fuel therein, said arm communicating with the atmosphere, and means subjecting the other arm to suction above the 115 throttle to lift the fuel therein above the normal level, the reduction of said suction permitting a drop of the fuel in the last mentioned arm and a consequent rise of the fuel in the first named arm above the fuel 120 nozzle leading therefrom.

3. In a carbureter, a carbureting chamber having an air inlet and a mixture outlet, a throttle controlling said outlet, a constant level liquid fuel supply chamber, a fuel 125 nozzle extending into said carbureting chamber and fed from said supply chamber, a U-shaped well fed from said supply chamber, and a fuel nozzle leading from one arm of said well above the normal level of 130

liquid fuel therein, said arm communicating with the atmosphere, a restricted connection between the other arm and atmosphere, means subjecting said other arm to suction to lift the fuel therein above the normal level, the reduction of such suction permitting a drop of the fuel level in said other arm and consequent flow of fuel to the first named arm and a rise in fuel level therein above the fuel nozzle leading therefrom.

4. In a carbureter, a carbureting chamber having an air inlet and a mixture outlet, a throttle controlling said outlet, a constant level liquid fuel supply chamber, a fuel nozzle extending into said carbureting chamber and fed from said supply chamber, a

U-shaped well fed by a restricted passage from said supply chamber, a fuel nozzle leading from one arm of said well above the normal level of liquid therein, said arm communicating with the atmosphere, and means subjecting the other arm to suction to lift the fuel therein above the normal level, the reduction of said suction permitting a drop of fuel level in said other arm and a rise of the fuel level in the first named arm above the fuel nozzle leading therefrom.

In witness whereof, I hereunto subscribe my name this 19th day of August, A. D. 30 1915.

FRANK C. MOCK.
